UNITED STATES PATENT OFFICE.

WALTER B. KENNEDY, OF SAN FRANCISCO, CALIFORNIA.

ELECTRICAL-CIRCUIT CONTROL.

Application filed October 23, 1922. Serial No. 596,515.

To all whom it may concern:

Be it known that I, WALTER B. KENNEDY, a citizen of the United States, residing in the city and county of San Francisco and State of California, have invented a new and useful Improvement in an Electrical-Circuit Control, of which the following is a specification.

My invention relates to improvements in controlling devices for electrical circuits whereby the flow of current through an electrical element may be regulated to meet the varied requirements.

The primary object of my invention is to provide an improved circuit control.

Another object is to provide an improved device whereby the flow of current to an electrical element may be varied through wide limits.

A further object of my invention is to provide an improved device of the character described for cutting a desired amount of resistance into a circuit and arranged to permit the resistance to be entirely cut out of the circuit when desired.

A still further object is to provide an improved device wherein a single slidable contact may be utilized for introducing a variable resistance into a circuit through an electrical heating element and for breaking the circuit through the resistance independently of the circuit through said element.

Another object is to provide a device in which a single slidable element may be utilized for introducing a variable resistance into a circuit through an electrical heating element and for breaking the circuit through said resistance and heating element simultaneously or independently as desired.

A further object is to provide an improved construction adapted to facilitate the manufacture and assembly of the device.

I accomplish these and other objects by means of the device disclosed in the drawings forming a part of the present specification wherein like characters of reference are used to designate similar parts throughout said specification and drawings, and in which:

Fig. 1 is a broken side elevation of an electrical heating device and connections thereto showing my improved circuit control applied thereto.

Fig. 2 is an enlarged side elevation of my

control device with one-half of the housing removed.

Fig. 3 is a transverse section taken upon the line 3-3 of Fig. 2 in the direction indicated.

Fig. 4 is a broken side elevation showing the manner in which the circuit is broken when the contact is moved to one extreme position.

Fig. 5 is a conventional wiring diagram of the electric circuit.

Referring to the drawings the numeral 1 is used to designate a resistance coil wound upon a suitable core 2. The ends of the coil 1 are connected to contacts 3 which are normally engaged by spring contacts 4 secured upon opposite ends of the core in any convenient manner. A conductive bar 6 is mounted in spaced parallel relation to the coil 1, this being accomplished in the preferred construction shown in the drawings by securing the bar between flanges 7 formed at the ends of the core 2. A contact member 8 is slidably mounted upon the bar 6, said member 8 being provided with an extension 9 arranged to form electrical contact with the coil 1 at any point along the adjacent side thereof.

The coil 2 is preferably enclosed in a housing 11 made of insulating material and formed in recessed halves secured together by screws 12 or other suitable securing means. The housing members are grooved as at 14 upon their inner sides to receive the flanges 7 of the core 2 and thereby hold the core and coil in a fixed position within the housing. Recesses 16 are formed within the matching edges upon one side of the housing members to accommodate the bar 6 and contact member 8 and to form a slot 15 between the housing members when assembled through which a pin 17 carried by the contact member 8 extends. A button 18 is secured upon the outer end of the pin 17 by which the pin and the contact member 8 may be moved relatively to the coil 2.

The spring contacts 4 are so arranged as to be engaged by the contact member 8 and moved out of contact with the contacts 3 when the member 8 is moved to the corresponding extreme position along the bar 6. Springs 19 are mounted within the slot 15 to engage the pin 17 and retain the contact member 8 in either extreme position for a purpose hereinafter explained.

The control above described is intended to be connected into the circuit through an electrical element wherein it is desired to regulate the flow of current and is particularly useful in connection with electrical heating and lighting appliances. In the drawings I have shown the application of the device in connection with an electric flat iron 21 as one illustration of the principle and utility of the invention. In this application, the device is connected through a plug 23 or other suitable connection to a source of electrical energy, not shown, connection being made in the following manner. One of the spring contacts 4 is connected to one of the wires 24 of the cord 22 by a conductor 26 connected directly upon said wire between the plug 23 and the iron 21. The other wire 27 of the cord is severed and the end extending from the plug 23 is connected to the other spring contact 4. The severed end of the wire 27 which is attached to the iron 21 is connected to the conductive bar 6 from which electrical connection is made upon the coil 1 by means of the sliding contact member 8 and thence to the source of energy through the cord 22 and plug 23.

The operation of my invention is as follows: The control device being connected into the cord as above described and the electrical appliance connected to the source of electrical energy in the usual manner, the flow of current through the appliance will be dependent upon the position of the sliding contact member relative to the resistance coil 1. If we assume the contact 8 to be in the extreme left hand end of the coil it will be seen that the contact 8 will engage the spring contact 4 and the path of the current through the appliance 21 will be by way of the bar 6, contact 8, and spring contact 4 and the conductors connected thereto. In this position it will appear that the resistance coil 1 would be connected in parallel with the appliance 21 and both the resisting coil and the appliance would receive the full line voltage, and the full effect of the appliance be obtained. In this connection the flow of current through the coil 1 would be entirely wasted as no beneficial result would be obtained. To avoid such waste of energy I have arranged the contact member 8 in such manner that when moved slightly further to the position shown in dotted lines in Fig. 2, the spring contact 4 will be moved out of connection with the coil 1 and the circuit through the resistance coil thereby broken. The spring 19 is arranged to engage the pin 17 and hold the contact member 8 in this extreme position so that the circuit through the resistance coil will remain broken and the circuit through the appliance 21 operate in the usual manner.

If it is desired to reduce the flow of current through the appliance 21 as when it is desired to maintain a lower degree of heat the contact member 8 is moved to engage the coil 1 at the desired point. In this connection it will be noted that the resistance coil will be connected partly in parallel and partly in series with the appliance, the portion of the coil in series depending upon the position of the contact member 8, relative thereto, only the last three laminations being thus connected when the contact is in the position shown in full lines in Fig. 2 of the drawings.

As a member 8 is moved further to the right it will be noted that as the end of the coil is approached substantially all of the coil will be in series with the appliance 21 and the flow of current therethrough will be accordingly diminished until at the extreme end of the coil connection will be made back upon the wire 24 through the spring contact 4 and its connections. When the contact member 8 is in this position there will be no voltage drop across the appliance 21 and as a result no current will flow and there will be no heating effect obtained whatever. Under these conditions the current would, of course, continue to flow through the resistance coil. In order to break the circuit through the coil I have so arranged that a further movement of the contact 8 will operate to move the spring contact 4 out of engagement with its contact 3 and thereby break the circuit through the resistance coil as well as through the appliance 21. The pin 17 is engaged and the contact member 8 held in the extreme position shown in dotted lines in Fig. 4 of the drawings by a spring 19 in the same manner as at the first described limit of movement. When the appliance is not in use the cord 22 should be disconnected from the source of energy at the plug 23 in order to prevent an inadvertent movement of the contact 22 such as might result in a continued consumption of power through the coil 1.

The cord 22 is introduced into the housing 11 through apertures 28 in the ends thereof and securely connected in the manner described, thus becoming a permanent part of the usual cord.

The housing and coil may be made of an extremely light and compact construction especially adapted to household requirements. While I have illustrated my invention as applied in connection with an electric flat iron it is obvious that it is equally suited for use with many other electrical appliances wherein it is desired to periodically control the heating and lighting effects resulting from the flow of current therethrough. The construction of the several elements entering into the structure of

my invention is also subject to wide variation in form and arrangement without departing from the spirit of my invention. I, therefore, do not restrict myself to the precise disclosure made in the drawings but desire to avail myself of all modifications which may fall within the scope of the appended claims.

Having thus described my invention what I claim as new and desire to secure by Letters Patent is:

1. An electrical circuit control comprising a resistance coil having opposite ends thereof connected to feed and return conductors connected to a source of electrical energy, one of which conductors is connected with an electrical heating element; a contact slidably mounted adjacent the resistance and arranged to be moved relative thereto to form electrical connection therewith at various points therealong, said contact being electrically connected to the heating element whereby a circuit may be completed through said heating element and a desired portion of the resistance.

2. An electrical circuit control comprising a resistance coil having opposite ends thereof connected to feed and return conductors connected to a source of electrical energy, one of which conductors is connected with an electrical heating element; a contact slidably mounted adjacent the resistance and arranged to be moved relative thereto to form electrical connection therewith at various points therealong, said contact being electrically connected to the heating element whereby a circuit may be completed through said heating element and a desired portion of the resistance; and means for breaking the circuit through the resistance independently from the heating element.

3. An electrical circuit control comprising a resistance coil having opposite ends thereof connected to feed and return conductors connected to a source of electrical energy one of which conductors is connected with an electrical heating element; a contact slidably mounted adjacent the resistance and arranged to be moved relative thereto to form electrical connection therewith at various points therealong, said contact being electrically connected to the heating element whereby a circuit may be completed through said heating element and a desired portion of the resistance; and means actuated by the sliding contact for breaking the circuit through the resistance and the heating element.

4. An electrical circuit control comprising a resistance; spring contacts normally connecting opposite ends of said resistance with feed and return conductors connected with a source of electrical energy; and a contact slidably mounted adjacent the re-

sistance and movable relative thereto to engage said resistance at various points therealong, said contact being electrically connected to a heating element receiving one of the conductors, whereby a circuit may be completed through said heating element and a desired portion of the resistance; said slidable contact being arranged to actuate the spring contact at one end of the resistance to break the circuit through said resistance independently from the heating element.

5. An electrical circuit control comprising a resistance; spring contacts normally connecting opposite ends of said resistance with feed and return conductors connected with a source of electrical energy; and a contact slidably mounted adjacent the resistance and movable relative thereto to engage said resistance at various points therealong, said contact being electrically connected to a heating element receiving one of the conductors, whereby a circuit may be completed through said heating element and a desired portion of the resistance, said slidably contact being arranged to actuate the spring contact at one end of the resistance to break the circuit through said resistance independently from the heating element, and also arranged to actuate the spring contact at the other end of the coil to break the circuit through both the heating element and the resistance.

6. An electrical circuit control comprising a resistance coil; a spring contact mounted at one end of the coil and arranged to normally connect said end with one of a pair of conductors connected to a heating element, said conductor being also connected to a source of electrical energy; a conductive rod mounted in slightly spaced parallel relation to the resistance coil, said conductor being connected to the other of the conductors connected to the heating element; and a contact slidably mounted upon the conductive rod and arranged to normally form electrical contact with the coil at various points therealong to complete a circuit through the heating element and a desired portion of the coil, said contact being arranged to engage and form electrical connection with the spring contact at one end of the resistance coil and to move said spring contact out of contacting relation with the coil for independently breaking the circuit through the resistance when moved one extreme position, and also arranged to engage the spring contact at the other end of the coil and move said contact out of contacting relation with the resistance coil and break the current through the resistance and the heating element when said slidable contact is moved to its other extreme position.

7. An electrical circuit control comprising a resistance coil; a spring contact mounted

at one end of the coil and arranged to normally connect said end with one of a pair of conductors connected to a heating element, said conductor being also connected to a 5 source of electrical energy; a conductive rod mounted in slightly spaced parallel relation to the resistance coil, said conductor being connected to the other of the conductors connected to the heating element; a contact 10 slidably mounted upon the conductive rod and arranged to normally form electrical contact with the coil at various points therealong to complete a circuit through the heating element and a desired portion of the coil, 15 said contact being arranged to engage and form electrical connection with the spring contact at one end of the resistance coil and to move said spring contact out of contacting relation with the coil for independently 20 breaking the circuit through the resistance when moved one extreme position, and also arranged to engage the spring contact at the other end of the coil and move said contact out of contacting relation with the resistance 25 coil and break the current through the resistance and the heating element when said 30 slidable contact is moved to its other extreme position; and a housing arranged to enclose the coils and the several contacting elements.

8. An electrical circuit control comprising a resistance coil; a spring contact mounted at one end of the coil and arranged to normally connect said end with one of a pair 35 of conductors connected to a source of electrical energy; a conductive rod mounted in slightly spaced parallel relation to the resistance coil, said conductor being connected to the other of the conductors connected to a 40 heating element; a contact slidably mounted upon the conductive rod and arranged to normally form electrical contact with the coil at various points therealong to complete a circuit through the heating element and a desired portion of the coil, said contact being arranged to engage and form electrical connection with the spring contact at one 45 end of the resistance coil and to move said spring contact out of contacting relation with the coil for independently breaking the circuit through the resistance when

55 moved one extreme position, and also arranged to engage the spring contact at the other end of the coil and move said contact out of contacting relation with the resistance coil and break the current through the resistance and the heating element when said 60 slidable contact is moved to its other extreme position; and a housing arranged to enclose the coils and the several contacting elements; and means extending through a slot formed in the side of the housing for 65 operating the slidable contact.

9. An electrical circuit control comprising a resistance coil; a spring contact mounted 70 at one end of the coil and arranged to normally connect said end with one of a pair of conductors connected to a source of electrical energy; a conductive rod mounted in slightly spaced parallel relation to the resistance coil, said conductor being connected to the other of the conductors connected to a heating element; a contact slidably mounted upon the conductive rod and arranged to normally form electrical contact 75 with the coil at various points therealong to complete a circuit through the heating element and a desired portion of the coil, said contact being arranged to engage and form electrical connection with the spring contact 80 at one end of the resistance coil and to move said spring contact out of contacting relation with the coil for independently breaking the circuit through the resistance 85 when moved one extreme position, and also arranged to engage the spring contact at the other end of the coil and move said contact out of contacting relation with the resistance coil and break the current through the resistance and the heating element when 90 said slidable contact is moved to its other extreme position; a housing arranged to enclose the coils and the several contacting elements; means extending through a slot formed in the side of the housing for operating the slidable contact; and means for 95 retaining the slidable contact in either extreme position.

In witness whereof I hereunto set my signature.

WALTER B. KENNEDY.
